BROACHING MACHINE

Francis J. Lapointe, Ann Arbor, Mich.

Application October 2, 1935, Serial No. 43,172

4 Claims. (Cl. 90—33)

My invention has for its object to provide a broaching machine having a manual feed device for disposing the work in position with reference to the draw head to enable ready insertion of the broach through the work and into the draw head. The manual feed device is of particular advantage when used for placing relatively heavy pieces of the work in position with reference to the bolster plate or part of the machine that sustains the pressure of the work while it is being broached and to receive and remove the work upon the completion of the broaching operation. Preferably the feed device is located so as to dispose the work in close proximity to the part that sustains the pressure of the work during the broaching operation and from which it receives the work in order to reduce the movement of the work when drawn against the work engaging part or when released from the broach upon the completion of the broaching operation.

The invention also provides means operated automatically by the movement of the feed device for releasing the machine control elements to enable manual manipulation of the control elements and for automatically producing operation of parts of the machine.

The invention also consists in means for automatically maintaining the control elements in their controlling positions until they have been displaced therefrom by operations of parts of the machine.

The invention may be contained in broach machines of different forms, and to illustrate a practical application of the invention, I have selected a broaching machine embodying the invention as an example of the various structures that contain the invention and shall describe the selected structure hereinafter, it being understood that certain features of my invention may be used to advantage without a corresponding use of other features of the invention and without departing from the spirit of the invention as presented in the claims. The particular structure selected is shown in the accompanying drawings and described in detail hereinafter.

Fig. 1 illustrates a side view of the machine. Fig. 2 illustrates a dog that coacts to lock one of the control elements of the machine in its neutral position. Fig. 3 illustrates a top view of an automatic switch that is operated by one of the movable elements of the machine when the element is located in a certain position with reference to a fixed part of the machine. Fig. 4 is a view of a vertical section of the machine. Fig. 5 is a view of a section taken on the plane of the line 5—5

indicated in Fig. 4. Fig. 6 is a detail of the automatic control switch, parts of which are shown in Fig. 3. Fig. 7 illustrates an adjustable stop for the feeding device to limit its work feeding movement. Fig. 8 is a view of a section of a 5 broach operating part of the machine. Fig. 9 illustrates a section showing the valves that control the broach actuating parts of the machine. Fig. 10 illustrates a view of a section of parts of the control elements of the machine. Fig. 11 10 illustrates diagrammatically the electric connection between electrically controlling and electro-magnetically controlled parts of the machine.

The broaching machine illustrated in the drawings is provided with a suitable base part 1 and frame 2 that may be enclosed together with the working parts of the machine by sheet metal side parts and hingedly connected parts. The machine is also provided with suitable ways 4 for guiding the hydraulically or operated pressure means that reciprocates the broach. Preferably the machine is provided with a movable cylinder 6 integrally formed with a relatively broad plate 5 whose edges are located in the ways 4 that operate to guide the cylinder in its reciprocatory movements as produced by a fixed piston 7. A suitable tube or pipe 8 of relatively large diameter is rigidly connected to the piston 7 and to the base 1. The piston 7 is provided with suitable passageways 9 that communicate with the interior of the cylinder 6 on the lower side of the piston 7 and with the interior of the pipe 8 to admit oil under pressure from the pipe 8 into the cylinder 6 and for exhausting or returning oil to the reservoir. The cylinder 6 is also provided with a suitable head 12 through which extends a pipe 13 that communicates with the cylinder 6 above the piston 7. The pipe 13 is sealed in the head 12 by suitable packing means of the form well known in the art. The end of the pipe 13 terminates 20 preferably in a position in close proximity to the upper side of the piston 12 to produce a maximum cylinder stroke. Suitable pipes 15 and 16 are connected to the pipes 8 and 13 and to the valve casing 17 through which oil under pressure may be 25 directed to the cylinder 6 on one side of the piston, and oil may be exhausted from the cylinder on the opposite side of the piston according to the direction in which movement of the cylinder 30 is to be induced by the hydraulic pressures transmitted through the oil.

The oil movement through the pipes 15 and 16 is controlled by a movable valve element 19 located in the casing which is controlled in its position by suitable manual control elements that 35

control the operations of the machine. The valve casing 17 is connected to a pump 20 by means of a pipe 21. The pump 20 may be driven by a suitable source of power. The pipe 21 is connected 5 to a passageway 22 that communicates with the chamber in which the valve element 19 is located. The valve element 19 is of the piston type, it being provided with a pair of channeled heads 23 and a pair of piston heads 24 that are slidably supported within the valve chamber of the valve casing 11. The piston heads 24, when operated alternately, open the passageways of the valve casing to which the pipes 15 and 16 are connected and are enabled, through the channels of the 10 channeled heads 23, to exhaust the cylinder from the end other than the one receiving the pressure through the pipe 21. The valve casing is provided with a passageway 25 that communicates with the valve chamber at its ends. The pipe 26 is connected to the passageway 25 and communicates with the interior of the reservoir 27 in which the pump 20 is located and from which it receives the oil that is subjected to pressure and transmitted through one or the other 15 of the pipes 15 or 16 to reciprocate the movable cylinder 6.

The valve element 19 is operated by the manual control means of the machine. The machine is provided with a lever 30 that is supported on a 20 shaft 31 located in suitable bearings formed in the frame 2 of the machine and is provided with an arm 32 that is connected to the valve rod 33, and when the lever 30 is operated, the movable valve element 19 is slidably moved in the valve casing 17 to shift the movable valve element to direct the pressure and return flow of the oil to reciprocate the cylinder.

The cylinder 6 and its heavy guide plate 5 is provided with an over-hanging draw plate or 25 bracket 36 braced by the wings 35 and to which is connected a draw head 37 having means for automatically connecting the draw head with a broach, such as the broach 38, upon movement of the cylinder in advance of its working stroke and for automatically disconnecting the broach 30 from the draw head upon the completion of the return of the cylinder. The draw head 37 is of the type wherein pressure of a part of the draw head against a fixed part of the machine releases 35 the broach, and upon movement of the draw head from said fixed part and a following movement of the broach, it connects the broach with the draw head. Also, upon engagement of the fixed part upon the return of the draw head, the broach 40 is released.

In the usual operation of the broaching machine, the work is disposed intermediate the broach and a work supporting part of the machine, and the broach is inserted through the work 45 and into the draw head and is maintained in that position until the draw head is moved away from the work supporting part of the machine, whereupon the draw head operates to lock the broach to the draw head and draw the broach through 50 the work.

The broaching machine is provided with a 55 work engaging table or bracket 39 that is secured to the frame of the machine and may be provided with a suitable fixture 40 for holding the work 60 in a desired fixed position to locate the opening that is to be finished or cut by the broach in alignment with the movement of the draw head. Thus the draw head may engage the bracket 39, or the fixture 40, or any other suitable fixed part 65 that will permit movement of the broach head 70

into the draw head. Also the machine is provided with means for withdrawing the broach from the draw head in order to enable placement of the work in position with reference to the draw head, and to subsequently raise the broach to insert it 5 through the work and into the draw head, and to follow the draw head in its initial movement until the draw head engages the end of the broach.

In the form of construction shown, the broaching machine is provided with a pressure means 10 for receiving the broach from the draw head and returning it to the draw head comprising a piston and cylinder supported on the shelf 42 of the machine. Preferably the piston is fixed, and the cylinder 43 is slidably supported on a pair of rods 44 that depend from the shelf 42 by means of a 15 pair of wings having sleeves 45. The extent of movement of the cylinder may be limited by suitable rings 46 that are secured to the ends of the rods 44 by means of the nuts 47. A piston 48 is supported by a pair of depending tubes 49 and 20 50 coaxially disposed, one within the other, and communicating with a head 51 supported on the shelf 42 and having passageways that communicate with the interior of the pipes 49 and 50. The pipes communicate with the cylinder on opposite 25 sides of the piston.

The head 51 is connected by means of the pipes 52 and 53 with the valve casing 17 that also has passageways controlled by a piston valve 54 similar in form to the piston valve 19 except that it 30 is smaller. It is provided with the channeled heads 55 and the piston heads 56 that slidably move in the valve chamber 57. The valve casing 17 is also provided with a passageway 58 that extends to opposite ends of the valve casing and 35 is connected to the return pipe 59 that communicates with the interior of the reservoir 27. The heads 55 are channeled to permit exhaustion of the oil from the parts of the cylinder 43 located on one or the other of the sides of the piston 48. 40 Oil under pressure is directed from the pump 60 through the pipe 61 shown broken in Fig. 4, to the passageway 62 in the casing 17, whereby oil may be directed through either the pipe 52 or the pipe 53 to the cylinder 43 on one side of the piston 48 45 and exhausted through the other side of the piston according to the position of the movable valve member 54.

The movable valve member 54 is controlled electro-magnetically by switches that are opened 55 and closed by the feeding means. The work is fed into position to locate the work in alignment with the broach and the draw head by means of a work carrying slide 64 located in guide ways 65 that may be connected to the work supporting 60 bracket 39. The work carrying slide is located so as to slidably support the work and move it into a position such that the opening that is to be finished or cut is disposed in alignment with the broach and the draw head. It is particularly 65 adapted for use where the pieces of the work are relatively heavy. It affords a means for accurately locating the work in advance of the initial operation of the machine and the engagement of the broach. The work carrying slide 64 70 may be provided with a fixture 63 that may be shaped to conform to the exterior of the work, and to position the slide accurately with reference to the opening and the draw head. The guide ways may be provided with a suitable ad- 75

justable stop 66 that will limit the inward movement of the work carrying slide 64 to dispose the work so as to locate the opening to be cut or finished accurately with respect to the draw head 5 and the broach.

Inasmuch as the broach is raised to cause its head and the shank to pass through the work when the work has been accurately positioned, a means is preferably provided whereby the work carrying slide electrically controls the operation of the cylinder 43 to raise the broach 38 and pass its shank through the work and the head of the broach into the draw head 37 and also to press the locking head 67 against the head 37 10 and follow the head 37 a short distance and until the broach head 67 is locked in the draw head 37. A spring pressed switch 70 is located in position in one of the ways 65 to close the circuit by the work carrying slide 64 substantially at the time 15 that the slide reaches the limit of its inward movement to dispose the work in position. The switch 70 is located in the circuit of the main lines 71 and 72, and when closed the current flows through a solenoid 73 and a solenoid 74. The core of the solenoid 74 is connected to the valve rod 75 and operates to raise the movable valve member 54 against the tension of the spring 76. The spring 76 is connected to the valve rod 75 20 and to the valve casing 17 and operates to return the movable valve member to its initial position when the solenoid 74 is de-energized. When, therefore, the work carrying slide 64 is pushed inward against the stop 66, the movable valve member 54 is electro-magnetically actuated to 25 direct the flow of the oil from the oil pump 60 through the pipe 52, the pipe 49 to the interior of the cylinder 43 at a point above the piston 48 and cause the cylinder 43 to rise. The cylinder 43 is provided with a bracket 78 having a seat 30 for receiving a part 80 projecting centrally 30 from the lower end of the broach 38. The broach 38 is supported and held in alignment with the draw head 37 by the seat 79. The cylinder 43 moves the locking head 67 of the broach through 35 the work and into the draw head and presses the upper end of the locking head 67 against the draw head 37 when the switch 70 is closed by the slide.

When the broach has been located in position to be locked into the draw head, the cylinder 6 is raised to cause the broach to perform its working stroke. The lever 30 is lowered to raise the movable valve member 19 and direct the flow of the fluid through the pipe 16 to a point 40 above the piston 7. The lever 30 may be connected to a sleeve slidably supported in a bracket 83 secured to the side of the machine. The lever 30 is connected to the sleeve 82 by means of the pin 84. A dog 85 is located in a socket part 45 formed on the bracket 83. The dog 85 is spring pressed by means of the spring 87 located intermediate the dog 85 and a plug 88 threaded into the end of the socket. The sleeve 82 is provided with annular notches or recesses 89, and when the lever 30 is moved downward, it is moved down until the dog engages the upper 50 of the recesses 89 and the lever is held in position. When the lever 30 is raised, the dog 85 engages in the intermediate recess 89 which is the neutral position of the lever. When the lever 55 is further raised, the dog 85 engages in the lower of the recesses 89. Thus, the dog 85 operates to hold the lever 30 in the position to which it is moved.

The sleeve 82, when located in its normal posi-

tion, is held locked by means of a pair of locking members or cams 92 located at the ends of the sleeve 82 and disposed so as to normally engage opposite ends of the sleeve 82 and prevent movement of the sleeve 82, and consequently prevent 5 movement of the lever 30 until the locking cams are moved from their position of engagement with the ends of the sleeve 82.

The cams 92 are pivotally mounted on brackets 93, and rods 94 are connected to the locking cams 10 92 and to cores 95 of the solenoids 73 and 96. When, therefore, the work carrying slide 64 is pushed inwardly to close the switch 70, it establishes a circuit, not only through the solenoid 74 to operate the movable valve member 54, but 15 also the solenoid 73 which removes the locking cam 92 from the lower end of the sleeve 82 and permits the downward movement of the lever 30 to raise the movable valve member 19 and direct oil under pressure into the upper end of 20 the cylinder 6.

The cylinder 6 then moves the draw head upward, and the continued pressure of the oil in the upper end of the cylinder 43 pushes the broach 38 upward against the draw head and 25 moves the broach upward with the upward movement of the cylinder 6 until after the draw head locks the head of the broach to the draw head. Continued upward movement of the cylinder 6 draws the broach through the work until the 30 broach completes its cutting stroke, whereupon the lever 30 is returned to its normal position to restore the movable valve member 19 to normal position.

The lever 30 is restored to its normal position 35 by means of the rod 98 that is connected to a bracket 99 that may be secured to the wings or braces 35 of the drawhead bracket 36. The rod 98 is provided with a pair of adjustable stops 100 and 101. The stop 100 engages the sleeve 40 45 82. The broach is carried upward until the working stroke of the broach is completed and the stop 100 engages and moves the sleeve 82 until it engages the locking cam 92 and is engaged by the dog 85 in the central recess 89 that 45 locks the lever in its neutral position. Meantime the solenoid 74 is maintained energized which maintains the movable valve member 54 in position to maintain pressure in the upper end of the cylinder 43 to hold the bracket 78 in its 50 uppermost position.

The broach having been drawn through the work, the work carrying slide 64 is withdrawn which opens the switch 70. To prevent the reverse movement of the cylinder 43 an auxiliary 55 circuit through the solenoid 74 is closed by means of a spring pressed switch 103. The switch 103 is suitably supported in the shell 104 and has an arm 105 that carries a roller 106, and the bracket 99 is provided with a cam 107 that 60 may be positioned to operate the roller 106 when the drawhead returns. The switch 103 is normally maintained open and is closed when the rod 98 is drawn from its normal position, namely when the drawhead is lifted from the work engaging bracket 39. The circuit to the solenoid 74 is not only through the switch 70, but also through the switch 103, and upon withdrawal of the work carrying slide 64 to open the switch 70, the switch 103 maintains the solenoid 74 energized, and the cylinder 43 is held in its uppermost position.

When the slide is withdrawn from beneath the work engaging bracket 39, the switch 108 is operated. The switch 108 is a spring pressed 75

switch similar in form to the switch 70, and is located in one of the guideways 65 of the slide and so disposed therein as to be operated upon the withdrawal of the slide. The switch 108 completes the circuit from the main line 72 to the solenoid 96 that operates to actuate the upper of the cams 92 and withdraw the cam from the end of the sleeve 82 whereupon the lever 30 may be operated to lower the valve member 19 and cause the return movement of the cylinder 6. Return movement is prevented by the upper of the cams 92 which holds the sleeve 82 locked against manual movement to cause the return of the cylinder until the work is removed from beneath the broach, that is, until the switch 108 is closed. This prevents damage to the work and the broach. It also prevents forcing the work against the slide 64. The work having been removed, the broach moves down to its seat 79 located on the bracket 78, the seat being held in its delivery position by the continued energization of the coil 74 which is maintained closed, notwithstanding the opening of the switch 70. The drawhead pushes the lower cylinder 43 the distance that the cylinder 43 followed the drawhead upward upon the initial rise of the drawhead. As the drawhead 37 engages the fixture 40 or the bracket 39 or other fixed part of the machine from whence it started upward and releases the broach, the switch 103 is opened by the cam 107, and the solenoid is deenergized, and the spring 76 moves the movable valve member 54 downward and in position where the pressure is directed through the pipes 53 to the lower end of the cylinder 43 to move the cylinder 43 and the broach supporting bracket 78 downward and withdraw the broach beneath the work carrying slide 64. Also, as the cylinder 6 approaches its neutral position, the sleeve 82 is engaged by the stop 101 located on the rod 98 which moves the lever 30 to its neutral position, and again the sleeve is engaged by the dog 85 in the central recess 89 to maintain the lever 30 in its neutral position. A succeeding piece of work is again placed upon the slide, and the slide moved inward to open the switch 108 which deenergizes the solenoid 96 and permits the cam 92 to engage the end of the sleeve 82. Also, the switch 70 is closed and the succeeding operations of the machine are performed as described.

I claim:

1. In a broaching machine, a drawhead, means for reciprocating the drawhead, a lever for con-

trolling said means, a locking means for preventing the movement of the lever, a work engaging member, a work supporting member operable to move the work in broach engaging position, means operated by the work supporting member for controlling the lever locking means for preventing movement of the lever until the work supporting member has moved the work into broach engaging position.

2. In a broaching machine, a draw head, a hydraulic pressure means for reciprocating the draw head, a source of supply of liquid under pressure, a valve directing liquid under pressure to the hydraulic pressure means, a lever for operating the said valve, a rod operated by the pressure means, a sleeve located on the rod and connected to the lever, adjustable stops located on the rod and on opposite sides of the sleeve for engaging the ends of the sleeve for moving the lever, means for yieldingly resisting the movement of the sleeve.

3. In a broaching machine, a draw head, means for operating the draw head, a broach and a broach moving means for moving the broach to the draw head, a work engaging member located intermediate the draw head and the said broach moving means for holding the work upon operation of the draw head, a movable work supporting member movable between the said work engaging member and the said broach moving means for locating the work above the broach and in position to be engaged by the work engaging member when the broach is operated by the draw head, and means operated by the movable work supporting member for initiating the movement of the broach moving means, and means controlled by the movement of the said broach moving means for initiating the operation of the draw head by the first named means.

4. In a broaching machine, a work engaging member, a work supporting member slideably supported with respect to the work engaging member, a draw head located on one side of the work engaging member, a broach moving means for supporting the broach on the other side of the work engaging member, means operated by the slide member for initiating the sequential operation of the broach moving means and the draw head, the said broach operable to engage and release the work from the work supporting member and press the work against the work engaging member as the broach is moved.

FRANCIS J. LAPOINTE.
